UNITED STATES PATENT OFFICE.

CHARLES W. HUNTINGTON AND EDWIN A. TRACY, OF NORWICH, CONNECTICUT, ASSIGNORS TO WILLIAM A. AIKEN, OF SAME PLACE.

SHOE-REST.

SPECIFICATION forming part of Letters Patent No. 388,685, dated August 28, 1888.

Application filed June 27, 1888. Serial No. 278,346. (No model.)

To all whom it may concern:

Be it known that we, CHARLES W. HUNTINGTON and EDWIN A. TRACY, citizens of the United States, residing at Norwich, in the county of New London and State of Connecticut, have invented certain new and useful Improvements in Shoe-Supports for Display-Frames, which improvements are fully set forth and described in the following specification, reference being had to the accompanying two sheets of drawings.

Shoe-supports of this class have been commonly constructed heretofore of sheet-metal plates conforming in outline with the sole of a shoe or of wire bent to substantially the same outline. In said wire supports spring-clamps adapted to embrace the shoe sole or shank have also been provided; but in all such devices, so far as we are acquainted with them, the shoe, if inclined or tipped out of a horizontal position, is likely to fall from its support or become more or less displaced. Such devices have been further objectionable for the reason that various sizes must be provided to support the almost endless variety and shapes of foot-gear. A small support could not well receive a large shoe, neither could a small shoe be satisfactorily displayed on a plate several sizes larger than its sole.

Our present invention is intended to overcome the difficulties or objections above recited by providing an adjustable clamp-support which may clasp the shoe-sole firmly enough to retain and exhibit it in any position, the connecting parts of said support being such that said clamp may be swiveled in any direction to expose different sides or portions of the shoe.

We have illustrated our said device and some of the ways in which it may be utilized in the annexed drawings, in which—

Figure 1 is an elevation of an individual or single stand shoe-support embodying our invention, and Fig. 2 shows two of our shoe-clamps applied to a bracket-arm. Fig. 3 is an enlarged perspective view of the clamp proper and its connected parts; and Fig. 4, a detached side view of the stud *h* and the nut *c'*, which in practice secure the clamp-plates to said stud. Figs. 5 and 6 show vertical sections of our said clamp and its connected parts

and illustrate means slightly different for controlling the swiveling of the same, all being described in detail hereinafter. Fig. 7 is a top view (reduced in size) of our clamp-plates, 55 illustrating the provision made for automatic adjustment to irregular or non-parallel edges of a shoe-sole. Fig. 8 is a perspective view of the binding-nut *c'*.

Referring to said drawings, the letters *a a'* indicate clamp-plates, made, preferably, of sheet metal, each formed with its outer end turned upward and slightly inward, as shown. The particular shape of the clamping jaws thus provided may be varied as circumstances or judgment may direct without departing from the spirit of our invention. The bases *a² a³* of the clamp-plates overlap each other and are provided with coincident slots *b*, thus allowing the plates in practice to be adjusted to or 70 from each other to clasp shoe-soles of greater or less width. Within slots *b* is a nut formed with a rib portion, *c*, and a flanged head, *c'*, the rib being about the same height as the united thickness of the bases *a² a³*. Said rib 75 *c* is intentionally made narrower than slots *b*, so that the jaws of the clamp-plates may have considerable lateral motion, as indicated in Fig. 7, thus allowing said jaws to adjust 80 themselves to the shape of the shoe-sole to be supported.

The letter *d* indicates a bar, usually of metal tube, whose office is to support the shoe-clamp. (See Fig. 2.) On this bar *d* is a collar, *e*, which is secured to said bar in any desired position 85 by a thumb-screw, *f*. The upper side of collar *e* is formed with a boss, *e'*, drilled to receive a stud, *h*, whose upper end is milled back to a shoulder and threaded to engage the nut *c c'*, above described.

In Fig. 6 the stud *h* is held rigidly in its seat in boss *e'* by a thumb-screw, *i*, while in Fig. 5 I have shown a construction that renders the set-screw *i* unnecessary. In said Fig. 5 the lower end of stud *h* is formed with a swelled 95 or conical head, *h'*, that rests in a correspondingly-shaped recess leading from the opening in collar *e* into the hole in boss *e'*. In assembling the several parts, stud *h* is passed upward through the tapped hole, which is to receive thumb-screw *f* before said thumb-screw is inserted. The conical head of stud *h* is of

such length that it projects downward and rests on bar *d*, which is fitted loosely in collar *e*. When it is desired to rigidly secure the collar and stud, the thumb-screw *f* is turned 5 home, which action forces bar *d* upward and crowds the tapered head of said stud tightly into its seat, effectually locking said parts together. Stud *h* is formed in Fig. 6 with an integral milled flange, *k*, by which it may be 10 grasped when it is desired to unscrew it from nut *c c'*. In Fig. 5 a similar flange is provided by forcing a milled collar, *k'*, on said stud after it is passed upward through boss *e'*.

A shoe-support substantially as above set 15 forth is of pleasing design, may be cheaply produced, and is so small that a fraction only of the shoe is hidden from view. Figs. 3, 5, and 6 show said support at about two-thirds its practical size.

20 The form of clamping-jaws illustrated in Fig. 6 is such that the spring of said jaws may be utilized in the act of removing a shoe-sole from their grasp. Said jaws, being formed of spring-brass or analogous material, will yield 25 or spring apart a distance sufficient to enable the operator to remove the shoe without being compelled to unscrew the binding-nut *c'*.

Having described our invention, we claim as new and wish to secure by Letters Patent—

30 1. A shoe support consisting of two overlapping plates having coincident slots to pro-

vide adjustment relative to each other and upturned ends to clasp the shoe, as set forth, in combination with a stand having a threaded end extending through said slots, a binding-nut 35 on said threaded end for interlocking said plates and stud, and a socketed stand for supporting the described shoe-support, all substantially as and for the purpose specified.

2. A shoe-support formed of two metallic 40 plates having upturned ends to clasp a shoe-sole and coincident slots, whereby adjustment relative to each other may be attained, a threaded supporting-stud projecting through said slots, and a binding-nut on said threaded 45 stud having one side formed as a rib somewhat less in width than said slots, substantially as and for the purpose specified.

3. In combination with bar *d*, a collar fitted 50 adjustably on said bar, a clamping-screw, *f*, a stud with milled head seated in said collar, a shoe-support formed of two overlapping slotted plates with upturned ends, as set forth, and a nut on said stud for clamping together the plates of said shoe-support, all substantially as and for the purpose specified. 55

CHARLES W. HUNTINGTON.
EDWIN A. TRACY.
